Primary Examiner—Caron D. Veynar*Assistant Examiner*—Ricky Pham(74) *Attorney, Agent, or Firm*—Black Lowe & Graham PLLC(57) **CLAIM**

I claim the ornamental design for the multi-chopper, as shown.

DESCRIPTION

FIG. 1 is a top perspective view of the multi-chopper, showing my new design;

FIG. 2 is a right side view of the multi-chopper;

FIG. 3 is a top view of the multi-chopper;

FIG. 4 is a front side view of the multi-chopper;

FIG. 5 is a back view of the multi-chopper;

FIG. 6 is a left side view of the multi-chopper; and,

FIG. 7 is a bottom view of the multi-chopper.
